UNITED STATES PATENT OFFICE

2,615,509

GAS BURNER HAVING MULTIPLE PRIMARY
AIR INLETSJames A. Whittington, Evanston, Ill., assignor of
one-half to Alice P. Whittington, Evanston, Ill.

Application January 29, 1949, Serial No. 73,590

1 Claim. (Cl. 158—99)

1 The present invention relates to gas burners, and more particularly to the type in which the fuel gas is projected in the form of a jet or jets coordinate with the supplying of a supporter of combustion, such as air, at such jet or jets, and also further supplying of the supporter of combustion to the mixture of gas and air for enhancing the mixture for burning the same without flash back or the like with various types of fuel gases having a wide range of heat values.

Among the objects of the invention is to provide a novel means for burning different kinds of fuel gas, such as natural gas, manufactured gas, and other kinds, or mixtures thereof having different B. t. u. values, at normal operating pressures thereof and without any adjustment of any part of the means, or any variation of construction of the means, or of any part of the means, so that the burner of the present invention is of universal use, and regardless of the normal operating or below normal operating pressure of the gas used, the proper and desired burning of the gas will occur without any flash back. When, in the present application, I refer to "normal operating pressures and pressures below such normal operating pressures," I mean those pressures recommended by the American Gas Association, set forth in Table 2, Page 31, Bulletin No. 10, of American Gas Association 1940, as follows:

Type of Gas	Assumed Gas Pressure In./H ₂ O
Coke Oven	3.5
Mixed	6.0
Natural	7.0
Butane	11.0

When employing butane, propane or like gases as the fuel gas, it is not necessary to effect any adjustment of the burner of my present invention, but it is necessary to use a gas injection orifice of a smaller diameter than that used with other fuel gases such as coke oven gas, natural gas, mixed gas, or the like, to prevent overgassing of the burner.

Other objects, advantages, capabilities, features, and the like are comprehended by the invention as will later appear, and as are inherently possessed by the invention.

Referring briefly to the drawings:

Fig. 1 is a vertical sectional view of an embodiment of the invention;

Fig. 2 is vertical and transverse sectional view

2 taken in a plane represented by line 2—2 in Fig. 1 of the drawings;

Fig. 3 is a view similar to that shown in Fig. 2 but of a modified form, and as taken in a plane represented by line 3—3 in Fig. 4 of the drawings;

Fig. 4 is a view in elevation of a part of the form shown in Fig. 3 of the drawings;

Fig. 5 is an elevational view of a further alternative form of the invention;

Fig. 6 is a transverse sectional view taken in a plane represented by line 6—6 in Fig. 5 of the drawings;

Fig. 7 is a part elevational and part sectional view taken in a plane represented by line 7—7 in Fig. 8 of the drawings of a further alternative form of invention; and,

Fig. 8 is a top plan view with a part shown in broken section of the form of invention shown 20 in Fig. 7.

Referring more in detail to the drawings, and first more particularly to the form shown in Figures 1 and 2, the burner comprises an elongated gas chamber 20 of any desired cross-sectional form, such as square as shown in Fig. 2, and at a suitable point, as at an end of the chamber 20, is connected a suitable gas supply duct or the like 21. The chamber 20 has an upper wall 22 provided with a plurality of suitably spaced gas orifices 23. The delivery end portion of the gas supply duct 21 may be suitably fitted or connected to a connector or like member 24 sealingly fitting in an end portion of the chamber 20. While only one gas duct 21 and plug 24 is shown at an end of the chamber 20, it is to be understood that the invention comprehends the providing of a similar duct and plug means or equivalent means at other points of the chamber 20, such as the other end thereof.

40 Spacedly above the upper or top wall 22 of the chamber 20 is provided a strip or bar 25 so as to provide between the bar 25 and the wall 22 an air space or the like 26 open, as at 27, at the sides. (See Fig. 2.) The altitude or width of 45 the air passage is such as to afford flow of air to the gas jet emerging or jetting from the gas orifice 23 to quickly mix with the gas jetting from said orifice. In the member or strip 25 are provided openings or holes 28 each of which is 50 defined by straight sides extending uniformly throughout the length thereof, and arranged in respective alignment with corresponding orifices 23 and each of such holes being of greater cross-sectional area than the corresponding orifice 23 55 so that the upward flow of the mixture of gas

and air will be of sufficient rate of flow to draw in additional air through the air space 29 above the member 25.

Spacedly above the member 25 is a similar strip or member 30 thus providing therebetween an air space 29 just above referred to, such space or the like 29 being open or having openings 31 at the sides for the free entry of air to the space 29. The member 30 is provided with orifices or openings 32 each of which is defined by straight sides extending uniformly throughout the length thereof, and arranged in respective alinement with the corresponding holes or orifices 28 in the member 25 and each of such holes 32 being of greater cross-sectional area than that of the corresponding opening or orifice 28 so that upward flow of the mixture will be of sufficient rate of flow to draw in additional air by way of the openings 31 and space 29. The altitude or width of the air passage 31-29 is such as to afford flow of air to the gas and air mixture stream emerging or jetting from the opening or orifice 28 to quickly mix with the mixture jetting from said opening or orifice. The altitude of the passage 29 is not critical and, hence, may vary within a reasonable range, but it is preferable for the altitude of the air passage 29 to be greater than the altitude of the air passage 26.

Spacedly above the member 30 is a similar strip or member 33 providing therebetween an air space or passage 34, such space or passage having openings or the like 35 at the sides for free entry of air to the space 34. The altitude of the passage or space 34-35 is preferably less than that of the space 29-31 but may be greater than or even about that of the altitude of the space 26-27.

The member 33 is provided with holes or openings 36 each of which is defined by straight sides extending uniformly throughout the length thereof, and arranged in respective alinement with the corresponding holes or orifices 32 in the member 30 and each of such holes 36 is of greater cross-sectional area than that of the corresponding opening or orifice 32 so that upward flow of the mixture will be of sufficient rate of flow to draw in additional air by way of the openings 35 and the space 34. The altitude or width of the air passage 34-35 is such as to afford flow of air to the gas and air mixture stream emerging or jetting from the opening or orifice 32 to quickly mix with the mixture jetting from said opening or orifice.

Above the member 33 at each opening 36 is a burner head or the like 37 having at its lower end a neck or the like 38 suitably fixed in sealing connection with the top of the strip 33 in circumscribed or encircling relation to opening 36 to establish direct communication between them, and from the neck 38 extend upwardly a pair of opposed tapering or inclined side walls 39, 39 providing therebetween a tapered or wedge like chamber 40, these walls having along their sides and at their ends spaced lips or flanges 41, 41 and 42, 42 so as to provide between said lips or flanges narrow elongated burner slots or orifices 43, 43 and 44, and at the lower ends of the walls 39, 39 is provided a sealing member or strip 45. The effective width of the burner slots or orifices 43, 43, and 44, when employed for the burning of manufactured gas is of the order of $\frac{3}{64}$ ", such width being more or less standardized for the various natural and artificial gases as fully set forth by specifications of the American Gas Association, appearing in the table on page 10, Bulle-

tin of American Gas Association, 1940. The burner or flame orifice 44-43-43 extends along the sides and along the end of the burner nozzle 37 so as to produce a U-shaped flat flame. The air at or outside such burner slot or orifice 44-43-43 will be in such proportional abundance as to cause combustion at or just beyond such slot or orifice. This is true regardless of the type of gas used and also regardless of variations in normal operating pressures and pressures below said normal operating pressures. When the pressure is low the aspirating effect at the openings or orifices 23, 28 and 32 will be low and, when the pressure is high the aspirating effect at the openings or orifices 23, 28 and 32 will be high, so that in any case approximately the same proportions of air to gas or to the gas mixture will always be in the same relation. It will be noted that the neck 38 of the burner head 37 has an internal diameter substantially equal to the diameter of the uppermost hole or opening 36 and greater than the diameter of the opening 32. By virtue of this construction air-gas mixture will pass freely and without interruption or restriction into the burner head 37 through the neck 38. This feature is clearly illustrated in Fig. 1 of the accompanying drawing.

The amount of primary air mixed with the stream of gas as it flows from gas orifice 23 through opening 36 is effected by the resistance to fluid flow through the burner, which resistance is affected by the area of the flame port 43-43-44. A greater extent of area of flame port 43-43-44 will permit a greater percentage of primary air to be injected by the momentum of the gas stream. Conversely, a lesser extent of area of the flame port 43-43-44 will permit a smaller percentage of primary air to be injected by the momentum of the gas stream, the gas input to this burner from gas orifice 23 remaining constant. One square inch of area of flame port 43-43-44 per 20,000 B. t. u.'s input per hour at normal gas pressure has been found to give very good results. The ratio of flame port area to B. t. u. input per hour may be varied considerably depending upon the air-gas ratio desired, and a port area of from one to four times the area of the inlet port of the neck of the burner head has been found to produce results which are entirely satisfactory. The determination of the proper port area for a given B. t. u. input per hour may be readily calculated in accordance with existing standards, as outlined, for example, in Table No. 3, page 65, Bulletin No. 10, of American Gas Association, 1940.

Referring now to Figs. 3 and 4, a gas chamber 45, corresponding to the gas chamber 20 of the form shown in Figs. 1 and 2, may be used, and it may be of any desired cross-sectional form, as round as shown, and at spaced points there along are provided hubs or necks 46 in which may be suitably connected orifice nozzle members or elements 47 provided with a stub 48 threaded or otherwise fixed to the hub or neck 46, and having a chamber 49, at the upper end of which is a gas orifice 50.

To the part 47 is fitted a tubular member 67 having spaced walls or web members 51, 52, 53 and 54 corresponding, respectively, to the members or parts 22, 25, 30 and 33 of the form of the present invention shown in Figs. 1 and 2, particularly in Fig. 2. The member 67 has a hub portion 55 to fit on and to the part 47, and the wall parts 51, 52, 53 and 54 are provided with openings or orifices 56, 57, 58 and 59 correspond-

ing, respectively, to the holes or orifices 23, 28, 32 and 36 in the device as shown in Fig. 2. It will be noted that the openings 57, 58, and 59 are each defined by straight sides extending uniformly throughout the length thereof and that the diameters of said openings increase progressively from opening 57 to opening 59. Between said wall parts 51, 52, 53 and 54 are provided air spaces or passages 60, 61 and 62 which have air entry parts 63, 64 and 65 provided in the cylindrical wall 66 of the structure. The gas jet orifice comprises the aligned orifices or parts 50 and 56 and corresponds to the gas orifice 23 in Fig. 2. The orifices 57, 58 and 59 correspond respectively to the orifices 28, 32 and 36 shown in Fig. 2. At the upper end of tubular member 67, a burner head 37 is attached to the part 54 in the same way as the burner head 37 is attached to the part 33 in Fig. 2. In this form of the present invention, the neck portion of the burner head 37 has an internal diameter substantially equal to the diameter of the uppermost hole or opening 59 and greater than the diameter of the opening 58, this construction permitting the air-gas mixture to pass freely and without interruption or restriction into the burner head 37 through the neck thereof. This device operates in the same way as the device shown in Figs. 1 and 2.

The thickness of the plate through which the orifices are formed is not critical, and burners of the present invention have been successfully operated with plates which vary in thickness from $\frac{1}{4}$ inch to $\frac{1}{8}$ inch. The size of the orifices is not critical, and burners of the present invention have been successfully operated with orifices of $\frac{1}{4}$ inch, $\frac{3}{8}$ inch, and $\frac{1}{2}$ inch in series, and $\frac{3}{8}$ inch, $\frac{1}{2}$ inch, and $\frac{5}{8}$ inch in series, with entirely satisfactory results in each instance. The spacing or distance between the plates is not critical, and burners of the present invention have been successfully operated with a distance of .085 inch to .125 inch between the gas orifice and the first plate, a distance of $\frac{1}{16}$ inch to $\frac{1}{4}$ inch between the first and second plates, and a distance of $\frac{1}{8}$ inch to $\frac{1}{8}$ inch between the second and third plates. The size or dimensions of the gas inlet orifice, the amount of primary air required for efficient combustion of the gas, and the dimension of the burner port where combustion takes place, are all well within the knowledge of one skilled in the art to which the present invention relates, and are readily ascertainable from such publications as Research Bulletin No. 13, "Fundamentals of Design of Atmospheric Gas Burner Ports," American Gas Association, 1942; Research Bulletin No. 26, "Primary Air Injection Characteristics of Atmospheric Gas Burners," American Gas Association Testing Laboratories, 1944; and many other pertinent publications, particularly those of the American Gas Association.

Referring to Figs. 5 and 6, the form of burner device there shown has a cylindrical wall 66 of the type shown in Figs. 3 and 4 and has a gas supply duct 68 corresponding to the gas orifice nozzle and chamber 47-48-49 shown in Fig. 3, said cylindrical wall 66 having air entries 63, 64 and 65, as shown in Fig. 3; and also interior parts (not shown in Fig. 5) corresponding to the interior parts shown in Fig. 3. The final mixture of gas and air moves to and through a duct 69 and thence to a burner head 70, corresponding to the burner head 37 shown in Figs. 1, 2, 3 and 4 of the drawings.

This burner head 70 comprises a mainly cylindrical shell part or wall member 71 enclosing a chamber 72, and provided along a side thereof with a pair of elongated lips or flanges 73, 73 defining therebetween a narrow elongated burner slot or orifice 74 corresponding to the burner slot or orifice 43, 43, and 44 shown in Fig. 1 of the accompanying drawings. The chamber member or burner head 70 has at its ends walls or wall members 75 and 76, which members are provided with holes 77 and 78 for the connection of a duct, such as duct 69, as to the wall member 75, or a closure plug or like member 79 fitted in the wall member 76. The duct 69 has an internal diameter greater than the diameter of the hole or opening in the wall or member between air entries 64 and 65 and, hence, the air-gas mixture may pass freely and without interruption or restriction into the burner head 70, and said duct 69 may be connected to either end of the burner head 70, as to either wall member 75 or 76, or, if desired, a duct 69 may be connected to each of the wall members 75, 76. The flame will burn at the flame slot or orifice 74 as in the case of the slot or orifices 43, 43, and 44 shown in Fig. 1 of the accompanying drawings.

Referring to Figs. 7 and 8, the type of cylindrical wall shown in Figs. 3, 4, and 5 is connected to a chamber member 80 by way of a duct 81 corresponding to the duct 69 shown in Fig. 5, or the duct means 47-48 shown in Fig. 3, the internal diameter of duct 81 being substantially equal to the diameter of the uppermost hole or opening in the uppermost member of the air-gas mixer and greater than the diameter of the hole or opening in the member immediately below said uppermost member, thus permitting the air-gas mixture to pass freely and without interruption or restriction into the burner head chamber 80. The chamber 80 has a plurality of openings 82 communicating with a plurality of ducts 83 leading to a plurality of burner heads 84 corresponding to the burner heads 37 shown in Figs. 1-4 of the accompanying drawings, or the burner head 70 of the form of the invention shown in Fig. 6 of said drawings. Each burner head 84 has an entry opening 85 and has converging sides or side walls 86 leading to a burner slot or orifice 87, and the burner head 84 also flares (see Fig. 7), so that the burner slot or orifice 87 is long and narrow, as shown in Figs. 7 and 8, such slot or orifice 87 corresponding to the slot or orifice 43, 43, and 44 of the forms of the present invention shown in Figs. 1-4 of the accompanying drawings, or to slot or orifice 74 shown in Figs. 5 and 6 of said drawings.

The operation and use of these forms are the same as described above in respect to those shown in Figs. 1-4 of the drawings.

The above referred to arrangement and the progressively increasing size of the holes or openings from the gas inlet orifice to the burner head, i. e. the holes or openings 28, 32, and 36 (see Fig. 2) and 57, 58 and 59 (see Fig. 3) of the air and gas mixers, constitute important features of the present invention. In the air-gas mixer shown in Fig. 2, the stream of gas issuing from gas orifice 23 passes upwardly and into the opening 28 of larger diameter than said orifice 23, which results in the creation of an annular zone of low pressure beneath the member 25 and adjacent and surrounding the lower edge of said opening 28, and extending upwardly through the lower portion of said opening, which low pressure zone 75 causes primary air to be sucked or drawn through

the air space 26 to mix with the gas with considerable turbulence to produce a thorough and intimate mixture of said primary air and gas as it flows through the hole or opening 28 toward the burner head. When the air-gas mixture issuing from the hole or opening 28 passes upwardly and into the opening 32 of larger diameter than said hole or opening 28, a second annular zone of low pressure is created beneath the member 30 and adjacent and surrounding the lower edge of said opening 32 and extending upwardly through the lower portion of said opening, which low pressure zone causes additional primary air to be sucked or drawn through the air space 29 to mix with the air-gas mixture with considerable turbulence to produce a thorough and intimate mixture of said additional primary air and the air-gas mixture as it flows through the hole or opening 32 toward the burner head. When the air-gas mixture issuing from the hole or opening 32 passes upwardly and into the neck 38 of burner head 37 of larger internal diameter than said hole or opening 32, a third annular zone of low pressure is created beneath the member 33 and adjacent and surrounding the lower edge of such portion 33, and extending upwardly through the lower portion of said neck, which low pressure zone causes still further primary air to be sucked or drawn through the air space 34 to mix with the air-gas mixture with considerable turbulence to produce a more thorough and intimate mixture of the additional primary air and the air-gas mixture as it flows into the burner head 37. Due to the fact that the holes or openings are each defined by straight sides extending uniformly throughout the length thereof and that the successive holes or openings increase in diameters from the gas orifice toward the burner head, the air-gas mixture does not proceed in a streamline flow but proceeds more in the nature of a column which, due to the progressive increase in the diameters of the straight side holes or openings, results in the creation of the aforementioned zones of low pressure beneath each of the successive members, which low pressure zones suck or draw into the gas stream the necessary primary air and create the turbulence necessary to insure a thorough and intimate mixture of the air and gas. These features in combination with the burner head having a chamber provided with an elongated port means open to the air and sufficient in extent to permit the injection of an amount of primary air proper for combustion of the gaseous fluid mass at said elongated port means, enables the burner of the present invention to be used for the burning of different kinds of fuel gas, such as natural gas, manufactured gas, and other kinds or mixtures thereof, having different B. t. u. values at normal operating pressures or pressures below normal operating pressures, without flash back or blow off, and without adjustment of the burner.

While I have herein described and upon the drawings shown a few embodiments illustrative

of the invention it is to be understood that other constructions, arrangements, details, features, and the like are comprehended by the invention without departing from the spirit of the invention.

Having thus disclosed the invention, I claim:

In a burner of the character disclosed and which has a gas supply means having an orifice for the jetting of gas under pressure therefrom, 10 a series of members arranged in parallel spaced relation and having progressively increasing sized orifices of fixed diameters located in alinement with each other and with the first mentioned orifice, each of said orifices in said members being 15 defined by straight sides extending uniformly throughout the length thereof, the member having the smallest sized orifice being nearest said first mentioned orifice, and the spaces between said members being fixed and forming air inlet 20 passages therebetween for affording flow of air through said passages and into the stream of gaseous fluid moving from an orifice to a next orifice of greater diameter, the flow of air-gas mixture from said gas supply orifice to the orifice of largest diameter creating a zone of low pressure beneath each of said members and adjacent and surrounding the lower edge of each orifice in said members and serving to draw in primary air through the spaces between said members to mix with the air-gas mixture, and a burner head member communicating with the last of said 30 series of orifices and having a neck portion with an internal bore of a diameter at least as great as the diameter of the orifice in the last member of said series to permit the air-gas mixture to pass freely and without restriction through said neck and into the burner head member, said burner head member having a chamber communicating with said neck and provided with an elongated port means open to the air and sufficient in extent to control the injection into the air-gas mixture as it passes through the orifices in the series of members of an amount of primary air required to provide a mixture of the proper air-gas ratio for combustion of the air-gas mixture at said elongated port means.

JAMES A. WHITTINGTON.
